FIG. 1

FIG. 4

FIG. 2

FIG. 5

FIG. 1 is a top plan view of a throw rug incorporating the design of the present invention.

FIG. 2 is a side elevation view of the throw rug depicted in FIG. 1.

FIG. 3 is a bottom plan view of the throw rug depicted in FIG. 1.

FIG. 4 is a top plan view of a throw rug constituting a different embodiment of the design of the present invention.

FIG. 5 is a side elevation view of the throw rug depicted in FIG. 4.

FIG. 6 is a bottom plan view of the throw rug depicted in FIG. 4.

FIG. 7 is a top plan view of a throw rug constituting a different embodiment of the design of the present invention.

FIG. 8 is a side elevation view of the throw rug depicted in FIG. 7.

FIG. 9 is a bottom plan view of the throw rug depicted in FIG. 7.

This is a continuation-in-part of my co-pending application Ser. No. D. 26,414, filed Dec. 11, 1970, and now abandoned.

The dominant feature of my design is that the shape of a human foot is distorted and lost in the throw rug overall design by reason of merger of the two side-by-side feet through an expanse of material not characteristic of either foot alone, or the two feet as placed side-by-side in a natural posture.

I claim:

The ornamental design for a throw rug, substantially as shown and described.
